FEEDING MECHANISM FOR SEWING-MACHINES.

1,231,824.

Specification of Letters Patent.

Patented July 3, 1917.

Original application filed March 26, 1903, Serial No. 149,651. Patent No. 922,646, dated May 25, 1909.
Divided and this application filed August 17, 1903. Serial No. 169,683.

To all whom it may concern:

Be it known that I, JOHN P. WEIS, a citizen of the United States, residing in Brooklyn, county of Kings, and State of New York, have invented a new and useful Improvement in Feeding Mechanism for Sewing-Machines, of which the following is a description.

My invention relates to sewing machines 10 of the type in which the binding and sewing are done simultaneously. Particularly, my invention relates to feeding mechanism by which bindings may be applied to all kinds of material, whether woven, knitted or otherwise produced, and in which the material and binding may be advanced to and fed from the stitch-forming mechanism simultaneously, evenly and without puckering or stretching the one relatively to the other. 15 My invention is specially useful in binding knit goods or loosely woven fabric, because such materials stretch excessively under the action of the feed and during the application of the binding, the latter being, 20 ordinarily, of closer weave or texture and not liable to stretch or stretch to the same extent. With these conditions of the work, difficulty has been found in mechanically applying the binding evenly and smoothly 25 and in a manner to overcome the tendency of the material and binding to pucker relatively and produce unsightly work.

One of the objects of my invention is to provide a feeding mechanism by which 30 bindings may be applied to all kinds of fabric with facility, rapidity, accuracy and neatness; and by which the tendency of the material and binding to pucker relatively is overcome and prevented.

Another object of my invention is to provide feeding means for controlling the conditions of the material and binding as they 35 are being fed to the stitch-forming mechanism; that is to say, operating upon the two, or manipulating them, in such manner as to produce precisely the condition desired at the stitch-making point, thus rendering it possible for the operator to produce and maintain evenness of work during the rapid 45 operation of the machine.

It is a further object of my invention to so enlarge the scope and operation of machines of the character stated as to enable them to perform, under the control of the

operator, a great variety of work, such as 55 fulling one piece of material relatively to another so as to take the stretch out of the same; or stretching one piece of material on or relatively to another so as to overcome any tendency to pucker or gather. 60

It is a still further object of my invention to provide a means by which any desired length of feed may be obtained during the operation of the machine and by which, after a maximum and minimum length of 65 feed have been determined upon, either one of the two extremes of feed may be obtained instantly and with certainty during the operation of the machine.

Another object of my invention is to provide mechanism for lifting the presser-foot and parts carried thereby, and mechanism for adjusting the feed, which two mechanisms can be actuated by the foot and knee of the operator, thus leaving the hands of 75 the latter entirely free for controlling the fabric in its passage to the stitch-forming mechanism.

Another object of my invention is to provide means by which the feed, carried by the 80 presser-foot, may be thrown out of action and rendered without function, without affecting the operation and functions of the lower feeding mechanism.

With the above objects in view, and others 85 which will be hereinafter noted, my invention consists in the parts, elements, features and combinations hereinafter described and claimed.

In the drawings:

Fig. 1 is a perspective view of the front 90 end of a machine showing my invention, the cloth-plate being omitted;

Fig. 2 is a vertical section approximately on the line 2-2 of Fig. 1;

Fig. 3 is an end elevation of that part of 95 the machine below the presser-bar;

Fig. 4 is a perspective showing the presser-foot and the feed-foot combined, and enlarged;

Fig. 5 is a detail perspective showing the parts of Fig. 4, separated and in position for assembling;

Fig. 6 is a detail showing the disposition 100 of the treadle, knee-rest and connecting parts;

Fig. 7 is a front elevation of the parts shown in Fig. 6; and

Fig. 8 is a top plan showing the throat-plate, folding guide and a section of the cloth-plate.

The main frame is indicated by 1; and 2, is the driving shaft; 3, the needle-bar which is caused to reciprocate vertically in the head of the machine. The stitch-forming mechanism has not been illustrated because the same forms no part of my invention and 10 because it is desired to clearly portray the important features of my invention.

The main shaft of the machine carries at its forward end a slotted disk 4, to which is adjustably connected, in usual manner, the 15 connecting rod 5, the outer end of which is connected to the outer end of a short shaft 6, carried by the feed-rocking frame 7, suitably journaled in the bed-plate of the machine. The short shaft 6, of the rocking 20 frame 7, has fixed thereto the feed-bar 8, which carries at its outer end the feed-dog 9, which may be connected thereto in any suitable manner. The feed-bar 8, has a guide-way therein in which reciprocates the feed- 25 bar 10, and which is given its feeding movements by mechanism hereafter noted. The two bars 8 and 10, are caused to have vertical movements by the same means, said means being an eccentric 11, on the main- 30 shaft, embraced by the bottom of the bar 8, and an angular arm 12, carried thereby.

The bar 10, carries a feed-dog 13, which is secured in usual manner in the end of the bar 10, by means of a screw 14. The feed 35 movement of the dog 9, is adjustable by means of the connection of the arm 5, with the disk 4, on the end of the shaft 2, in usual manner.

The feed movements of the dog 13 are 40 produced by means of the lever 15, pivoted at its lower end to the bed-plate of the machine, or a bracket thereof, and connected at its upper end pivotally with the bar 10, the connection being provided by means of 45 a screw 16, carrying a shoe or block 17, sliding in a longitudinal slot 18, in the lever 15, and said screw entering the bar 10, the shoe or block pivoting or swiveling on the screw. Hence, the disk 4, connection 5, rocking- 50 frame 7, arm 20, lever 15 and connections to the bar 10 are the feed-actuating elements, and said bar 10 would have feed movements regulated in degree for length of stitch by this means actuated by the main shaft without reference to any other elements in the machine; but, in addition, I have provided a duplex feed-regulating device and also a controlling means for the main bar 10, as presently described. The feed movements of 55 the bar 10, are regulated and controlled by means of the three-armed lever 19, journaled at its vertex to the short shaft 6, carried by the rocking frame 7. One arm 20, of the lever, is provided with a pivotally connected shoe 21, which embraces and slides 60

longitudinally on the lever 15. The arm 22, of the lever depends below its pivot and has connected thereto an angular bracket 23, by means of the screw 24, extending through a longitudinal slot 25, in the bracket, and the head of which screw clamps the bracket to the arm. A pin 26, is connected to the arm 22, and projects into the slot 25, of the bracket and acts as a limit for its adjustment in one direction and also prevents the bracket from swinging on its binding screw. The bracket has the angular portion 27, carrying a lug or stop 28, which contacts with the web portion of the rocking frame 7. The arm 22, is also provided with an angular 70 portion 29, carrying an adjustable stop or screw 30, which contacts with the opposite side of the web of the rocking frame 7, and is held in adjusted position by jam-nut 75 30*. By the addition of these particular elements I have provided a duplex feed-regulating device coöperating with the rocking-frame, because the angular-bracket 23, having the portion 27 which carries the pin 28, is adjustable on the depending-arm 22 of 80 the three-armed regulating lever, so as to regulate the movement of the arm 20 of said lever in one direction, by engaging the rocking-frame 7, while the depending-arm 22 has an angular portion 29, through which 85 passes the adjusting-screw 30 one end of which engages the said rocking-frame 7 to regulate the movement of the arm 20 in the opposite direction. The third arm 31, of 90 the lever has connected thereto, in any suitable manner, the chain 32, or other suitable device, which at its lower end, is connected to the treadle 33. At some point between its 95 ends, the chain, or other connection, is provided with a coiled spring 34, which when 100 pressure is applied to the treadle causes the chain to transmit a yielding pull upon the arm of the lever 19, and also prevents the vibration of the latter, caused by the rocking frame 7, during the operation of the machine, from being transmitted to the foot 105 on the treadle, as hereinafter noted. The interposition of the spring also takes up any slack in the chain which may occur between its ends and prevents the chain from rattling during the rapid operation of the machine. To still further prevent rattling and 110 to take up the slack in chain 32, the spring 35, connected to the chain and frame of the machine, is provided. Normally, the lever 115 19, is held with its arm 20, depressed by means of a spring 20*, that is to say, the spring keeps the stop 28, in contact with the web of frame 7, whatever the initial adjustment may be, and after the adjustment has been altered by depressing the arm 31, of lever 19, and the lever has been 120 released, the spring will return the stop 28, into contact with the web of the rocking-frame. Hence this mechanism, including 125 130

the treadle 33, connections 32, 34 and 35 and arm 31, provides and constitutes a mechanism for controlling the throw of feed-bar 10 independently of the movement of the feed-bar 8, and is under the control of the operator at all times, irrespective of the speed of the machine, and its operation does not affect the stitching or other operations of the machine in any respect.

- 10 The feed-bar 8, has connected thereto a vertically adjustable bracket piece 36, the same being rendered adjustable by means of the longitudinal slot 37, therein and the screw 38, passing therethrough into the bar. 15 At its upper end the bracket 36 has pivotally connected, or hinged, thereto an arm 39, the joint 40, between the two being close and tight in order that when said arm is turned down out of the way, below the cloth-plate, 20 the same will be prevented from moving and from rattling against the cloth-plate, the feed-bar or any other adjacent part of the machine, during the operation of the latter. At its upper end the arm 39, is provided 25 with an aperture or screw-threaded bore 41, coinciding with the smooth bore 42, in the rear end of an upper feed-foot 43, which is pivotally and slidably connected with the presser-foot 44. The clamping screw 45, which connects arm 39 and feed-foot 43, is provided with an enlarged head, a smooth stem portion 47, and a reduced screw-threaded portion 48, and detachably connects the arm 39, with the rear end of the 30 feeding-foot. The forward end of the foot is provided on its bottom with serrations or feed-teeth 49. The upper feeding-foot operates in an elongated slot 50, in the short portion 51, of the presser-foot. Said presser-foot 44, is also provided with the long portion 52, which bears upon and co-operates with the feed-dog 13. The presser-foot is provided with three vertical bars 53, 54, 55, extending longitudinally thereof and 35 providing between the same the slots or grooves 56, 57. In the groove 57, is suitably secured the downwardly depending lug 58, of the socket 59, which surrounds and is clamped to the presser-bar as usual. In the groove 56, the feeding-foot 43, slides and rocks on the screw 60, passing through the bar 53, slot 46, and into the bar 54. The feeding-foot operates oppositely to a smooth and solid part 62, of the throat-plate 61, and close to and beside the needle apertures in the throat-plate and the presser-foot. The rear portion of the short part of the presser-foot co-operates with the feed-dog 9. 40 The throat-plate of the machine set in the grooved slide-way of the cloth or work plate *a*, as usual, is provided with the elongated slot 63, for the reception of the lower feed-dogs, and as before stated with the solid portion 62, for receiving the pressure of
- the upper feed-foot. In advance of the said solid portion and the needle aperture of the throat-plate, the latter is provided with a depression 64, and with a side flange 65, the depression receiving the bottom of an elongated portion 67, of the binding-guide 66, and the flange receiving the side of such portion of the guide, thus keeping the latter firmly in proper position and permitting the said elongated portion of the guide to reach and operate close to the needle aperture in the throat plate. The binding guide includes the supporting plate 68, which is secured to the cloth-plate of the machine by means of the collar and fastening screw 69. Said plate has secured thereto a suitable strip-guide 70, and in advance thereof is provided with a curved strip-guide 71, which leads in the binding and properly turns the same upon the edge of the work. 45 The lower portion of the curved strip-guide at its base is provided with the forwardly extending portion 67, which lies in the depression and against the flange 65, of the throat-plate, close to and just in advance of the needle aperture as described. Extending parallel with the elongated portion of the guide, is a wire or small bar 72, secured at one end to the guide in any suitable manner, and at its forward end being bent at an angle to its main part as at 73, and extending in front of the elongated portion 67, of the guide and between the forward end of the latter and the needle aperture in the throat-plate. The forward end 50 of the supporting plate 68, is extended at 75, and provided with a vertical wall 76, affording a guide for the edge of the material or work. 55 The binding guide has not been described more in detail as the same does not form part of the invention in this case, but is, or may be, in all essential particulars the same as the binding guide shown in my Patent No. 922,646 granted May 25, 1909, of which this application is a division. 60 The presser-bar 59, is provided with the laterally projecting lug or arm 77, upon which bears the spring 78, which normally tends to hold the bar down to its work, and the pressure of which spring is regulated by the adjusting-screw 79, and jam-nut 80, extending through the frame of the machine and bearing upon said spring. A lever 81, pivoted to the arm of the machine, 65 has its forwardly extending arm 82, located under the lateral arm 77, of the presser-bar, said forward arm 82, being normally held out of contact with said lateral arm of the presser-bar by means of the coiled spring 83, secured to the arm of the lever and to any stationary part of the machine. The rear arm of the lever is connected by means of a chain 84, or other medium, with the arm 85, of a rock-shaft 86, secured to the 70 75 80 85 90 95 100 105 110 115 120 125 130

under side of the table which supports the machine, and the forward end of which rock-shaft is provided with a smooth bore through which extends a rod or arm 87, 5 adjustable in said bore by means of a screw 88, tapped into the end of the shaft. The arm 85, may be rendered adjustable in like manner. The other end of rod 87, is pivotally connected to a link 89, which in turn 10 is pivotally connected to the knee-rest 90, suitably pivoted to the table and depending in convenient position for operation. The depression of lever 81, is regulated by the adjustable stop 81^x, passing through the 15 frame of the machine,—see Fig. 1. This mechanism enables the operator to control the presser-foot and upper feed-foot so as to lift the same at will, or control their pressure on the work at any time.

20 A second treadle, located beside the treadle 33, which operates the feed-adjusting mechanism, controls a clutch-mechanism coöperating with a prime-mover which conveys power for operating the machine, as 25 is usual and unnecessary to illustrate.

The operation of my machine is as follows:

Primarily, it should be understood that one of the principal objects of my machine, 30 comprising the differential feeding mechanism and the binding mechanism, is to apply a binding to a piece of material, or a garment, smoothly and evenly, and without puckering or stretching the binding and the 35 material relatively. Another of the principal objects is to turn an absolutely angular corner on the work or garment with the binding; that is to say, in turning corners or angles it has heretofore been a difficult 40 matter to turn an angular corner evenly and perfectly, the normal tendency in turning corners, in applying the binding, being to round the corners and to stretch or turn under or, in some other manner, distort the 45 binding on the material. This obviously, is objectionable, makes unsightly work and reduces the value of the finished article.

By the mechanism which I have described above the binding can be applied evenly to 50 the material, without gathering or stretching the one relatively to the other, and angles can be neatly turned and the corners perfectly stitched down.

It should be noted that the feed-dog 13, 55 coöperates with the solid portion 52, of the presser-foot in clamping and feeding the body material; and that the feed-dog 9, co- 60 operates with the portion of the presser-foot in rear of the short foot 51, for feeding the binding in rear of the needle aperture; and that the upper feed-foot operates upon the upper fold of the binding and coöperates with the smooth portion of the throat-plate thereunder. The edge of the body material 65 is placed in the channel of the binding-guide

and is guided by the vertical portion 76, of the plate 68. The binding is led through the guide 70, which is suitably slotted for the purpose and then into the folder or guide 71, its lower fold being fed out of the end of 70 the extension 67, and under the extension 73, of the bar 72, and between the extension 73, of said bar, and the throat-plate of the machine. The throw of the feed-dog 9 is properly adjusted by suitably placing the connection between the arm 5, and the disk 4; and the throw of the feed dog 13 is suitably regulated, as to its initial throw, by adjusting the bracket 23, upon the depending arm 22, of the lever 19. Assuming the link 5 be adjusted on the disk 4 so as to give a normal feed movement to the feed-bar 8, and dog 9, the three-armed lever, in the adjustment shown, will, obviously, give a greater movement to the feed-bar 10 and dog 13, since the 80 connection 20—21 with the lever 15 is close to the pivot of the latter. This means that the main body of the work will be fulled to an extent often required in operating upon knitted goods, while the binding and that 85 edge of the garment to which the binding is applied will be fed slower with the result of giving to the garment, if it be the neck-opening of a shirt, the desired rounded effect. This coöperative action of the feed-dogs also overcomes the normal stretch of the work resulting from the body thereof hanging over the edge of the work-plate as the same is fed up to the stitching position. 90 If the lever-arm 31, under control of the operator, be manipulated so that the connection 20—21 be moved into concentric relation with the connection 16, both feed-bars will have identically the same feed stroke in identically the same time. Continuing the 100 sliding movement of the connection 20—21 until the center of the screw 21^x thereof is above the center of the screw 16, just so much as the one is above the other, just so much will the work be stretched; that is to 105 say, the feed-dog 13, operating upon the main body of the work, will be caused to travel slower and give a shorter feeding movement to the work, with the result that the work, for example knitted goods, will 110 be stretched or elongated to the desired extent in front of the stitching position during the normal feed action of the feed-dog 9, thus compensating for the natural stretch of 115 the binding material, or enabling the body and binding to be brought out evenly at the end of the seam or work. Ordinarily, the dog 13, will be caused to have a greater throw than the dog 9; and if at any time during the operation of the machine, it is 120 desirable to make the throw of the two dogs uniform the treadle 33, would be depressed, thus depressing arm 31, or lever 19, elevating arm 20, of said lever and causing the 125 pivotal connection of said arm with the le- 130

ver 15, to coincide with the pivotal connection between the lever 15, and the bar 10. Obviously, the throw of the dog 13, relatively to the throw of the dog 9, can be varied according to the position of the shoe 21, on the lever 15; and extremes of adjustment may be quickly and positively obtained by setting the adjustable stops 28, and 30, in predetermined positions, and such extremes of adjustment may be obtained during the rapid operation of the machine, and without affecting the stitch-forming mechanism, by depressing the arm 31, of the lever 19, as previously described. The spring 34, is interposed in the length of the chain 32, for the purpose, principally, of avoiding the vibration of the rocking frame 7, being transmitted, through the lever 19, and the chain 32, to the treadle 33, and to the foot of the operator which is constantly in contact therewith. Rattling of the chain on the treadle 33, is avoided by taking up the slack by means of the spring 35.

The knee-rest 90, is conveniently located for actuation by a side movement of the knee of the operator, such movement being transmitted through the link 89, and rod 87, to the rock-shaft 86, and thence through the arm 85, and chain 84, to lever 81, thus elevating its short arm 82, and lifting the presser-foot 44, from the work together with the feed-foot 43. This elevation of the preser-foot may be a great convenience at any time during the progress of sewing, and is necessary, of course, in placing the work to begin sewing. The knee-rest mechanism affords a convenient and ready means for lifting the two-feet and for leaving the hands of the operator free to properly manipulate the different parts of the work and attend to other necessary things above the work-plate.

The extensions 73, of the bar 72, prevents the curling, or sliding, or any lateral movement of the lower fold of the binding, as will be obvious. It will be clear from the drawings that the upper feed-foot operates directly upon the binding quite a distance in front of the needle and, as the machine is started, immediately feeds the binding at the same time the body material is fed, thus preventing any drag upon the binding and the stretching or distorting of the same relatively to the body material.

It should be noted that in sewing the binding to garments, or other work, of the character contemplated, it is necessary to manipulate the feeding-mechanism so that, in sewing along the straight edges, all the feed-dogs shall have the same speed, this being accomplished by depressing the treadle 33, and placing the connection 21*, coincident with the connection 16. But, when a corner has been turned, and the sewing is begun along a curved edge it is necessary to cause

the feed-dog 13, to feed faster than the dog 9 and the foot 43, which is accomplished by releasing the treadle 33, and allowing the arm 20, to be returned to the predetermined position by the spring 20.

The connection between the feed-foot and the bar 8, is removable as previously stated, this construction enabling the feed-foot to be thrown out of operation at any time it is desired to use the machine for any purpose for which said feed-foot would not be essential. The adjustable connection of the feed-foot with the bar 8, enables the foot to be regulated vertically and its pressure or grasp upon the work adjusted at will. Moreover, when very heavy work is being operated upon, the elevation of the presser-foot would lift the feed-foot too high for contact with and proper operation upon the binding. Hence, the adjustment of the plate 36, would be necessary. The pivotal connection between the arm 39, and the plate 36, enables the said arm to be turned down below the cloth-plate,—when the feed-foot is not in operation,—and the tight fit between the arm and the plate, previously described, prevents said arm from rattling against adjacent parts of the machine during the operation of the latter. Obviously, the vertical adjustment of the plate 36, will regulate the throw of the feed-foot and the latter may have an effective feed movement different in extent from the feed-dog 9; that is to say, the adjustment of plate 36, up or down, will control the pressure of the feed-foot upon the work and the pressure of said foot on the work controls the effective feed-movement. For example, if the plate 36 be lowered more than is shown in Fig. 2, the grip of the feed-foot on the work will be lighter and less positive and, consequently, the effective feed-movement of said foot will be less than that of the feed-dog 9 and the work will not be fed to the same extent by said foot as by said dog; but, with the adjustment shown in Fig. 2, the said foot and dog will operate upon the work with the same effect and their effective feed-movements will be the same.

From the above description it will be manifest that I have produced a feeding mechanism having characteristics which render it specially useful for the purpose of applying bindings to all kinds of goods, as set forth in my application above referred to; but, it is to be understood and it will be apparent, that by proper adjustments the feed may be caused to full one piece of goods upon another, or may be caused to feed several pieces of work with the same relative speed.

In the foregoing description, I have referred to two feed-bars, the one 8 carrying dog 9, and the one 10 carrying dog 13. Ordinarily, the feed-dog operating upon the

main fabric, or the one to which the binding is attached, would be designated the main feed-dog, and its bar the main feed-bar, while the other would be designated the auxiliary feed-dog, and its bar the auxiliary feed-bar. Inasmuch, however, as certain important features of my invention are applicable to either of the bars, and also inasmuch as the main body fabric, in certain machines to which the feeding mechanism may be applied, may be manipulated by a feed-dog having the location or disposition of my feed-dog 9 in the machine, I have avoided using the terms main and auxiliary dogs and main and auxiliary bars, excepting in a general sense, and not in a sense of special application to either of the bars. Furthermore, in the art the feed-dog, which operates upon the combined materials, viz., the body material and its applied binding, or upon the several layers of material being sewed together, is frequently called the main feed-dog. Therefore, in order to have my claims appended hereto understood and read in the broadest possible sense with reference to the manipulation, coöperation, and interaction of my two feed-dogs and their carrying bars, I have avoided the use of the terms main and auxiliary as applied to either of the dogs or their carrying bars. Hence, it is to be understood that, in the appended claims, where the terms main and auxiliary are employed, said terms apply equally, and interchangeably, to the said two bars and their dogs.

Having thus described my invention what I claim and desire to secure by Letters Patent is:

1. A feeding mechanism including three independent feeding-devices; common means for giving to said devices their vertical movements; common means for imparting the feed-movements to two of said devices; and independent means for imparting the feeding movement to the other of said devices.

2. A feeding mechanism comprising a feeding device located above the work-plate; a feeding device located below the work-plate; means for actuating the two feeding devices; means for regulating the throw of the lower feeding device including an actuating device located below the work-plate; and means for lifting the upper feeding device from the work including an actuating device located below the work-plate; the two actuating devices below the work-plate being under the control of the operator whereby adjustments of the said regulating means may be made and the upper feeding device raised from the work at the will of the operator.

3. A feeding mechanism comprising a plurality of feed-bars, each bar carrying a feed-dog and said dogs being arranged in par-

lelism; means for imparting feeding movements to said bars; means for regulating the feeding movements of said feed-bars; and treadle-operated means for controlling the throw of one of said bars independently of the other during the running of the machine and at the will of the operator. 70

4. A feeding mechanism comprising a plurality of feed-bars, each bar carrying a feed-dog and said dogs being arranged in parallelism; means for imparting feeding movements to said feed-bars; means for regulating the feeding movements of said feed-bars; and treadle-operated means for controlling the throw of one of said bars independently of the other, including a device whereby predetermined extremes of such throw may be instantly obtained. 75

5. A feeding mechanism for sewing machines comprising a feed-bar, and mechanism for imparting feeding movements to said bar, comprising a vibratory lever, and a three-armed lever, one arm of which latter has a sliding connection with said vibratory lever, another arm of which carries 90 means whereby the feeding movements may be regulated, and the other arm of which is accessibly presented for ready manipulation by the operator so as to control the feeding movements. 95

6. A feeding mechanism comprising a feed-bar; means for imparting feeding movements to said bar including a lever pivoted to the frame of the machine and having a sliding connection with said bar; a lever having a sliding connection with said first-named lever; means coöperating with said latter lever for controlling certain of the movements of said bar; and said last-named lever having an accessibly presented manipulating arm. 100

7. A feeding mechanism comprising a plurality of feed-bars; a rocking-frame to which said bars are connected; means for actuating said rocking-frame; a lever pivoted to the frame of the machine and having a sliding connection with one of said bars; a lever carried by said rocking-frame and having a sliding connection with said first-named lever; and means coöperating with said last-named lever for controlling its movements and thereby also controlling the movements of said first-named lever and its connected feed-bar. 110

8. A feeding mechanism for sewing machines comprising a reciprocating bar located below the cloth-plate, a rocking-frame, and a pivotal connection between said frame and bar; a feeding-foot pivotally supported and located above the cloth-plate; and a connection between the bar and foot including a plate adjustable on the bar, whereby the vertical position of the foot may be determined. 115

9. A feeding mechanism for sewing ma- 130

chines comprising a feeding-foot supported and operating above the cloth-plate, a reciprocating bar operating below the cloth-plate and carrying a feed-dog, and a connection 5 between the bar and foot including a plate adjustable on the bar, whereby the coöperation of said feed-dog and foot, and vertical position of the foot, may be determined.

10. A feeding mechanism for sewing machines comprising a feeding-foot supported and operating above the cloth-plate, a reciprocating bar operating below the cloth-plate and carrying a plurality of independently operable feed-dogs, means for actuating the 15 said dogs, and a connection between the feeding-foot and the bar including a plate adjustable on the bar, whereby the vertical position of the foot may be determined.

11. A feeding mechanism for sewing machines comprising a feeding-foot supported and operating above the cloth-plate, a four-motion feed-bar carrying a dog operating below the cloth-plate, means for actuating the bar, and a connection between the feeding-foot and bar including an adjustable bracket, whereby the vertical position of the 25 foot may be determined.

12. A feeding mechanism for sewing machines comprising a feeding-foot operating 30 above the cloth-plate, a support for said foot including a connection enabling the foot to have a rocking and sliding movement, a reciprocating bar operating below the cloth-plate, and a connection between the bar and 35 the foot including an adjustable bracket, whereby the vertical position of the foot may be determined.

13. A feeding mechanism for sewing machines comprising a reciprocating bar carrying a feed-dog, a feeding-foot supported independently of said bar, a detachable connection between the foot and the forward end of said bar including means whereby, when the connection is detached from the 45 foot, the said connection may be turned aside and held to avoid rattling or contact with adjacent parts.

14. A feeding mechanism for sewing machines, comprising a reciprocating bar carrying a feed-dog; a feeding-foot supported independently of said bar; means for actuating said bar including a rocking-frame; a connection hinged to said bar and pivoted to said foot whereby the latter is driven directly from said bar; and means whereby the pivot may be detached from said foot to enable the connection to be turned upon its hinge out of the way of the operator and the foot to be thus put out of action.

60 15. A feeding mechanism for sewing machines, comprising a feeding-foot suitably supported above the work-plate; a bar reciprocating below the work-plate; means for actuating said bar including a rocking-frame; a connecting-plate hinged at one end

to said bar and pivoted at its other end to said foot whereby the latter is driven directly from said bar; and means whereby the pivot may be detached from the foot to enable the connecting-plate to be turned 70 upon its hinge below the work-plate and the foot to be thus put out of action.

16. A feeding mechanism for sewing machines, including means for changing the throw or feed-movement during the operation of the machine, comprising a constantly moving member, a device under control of the operator, and a connection between the said member and device including an elastic section whereby the movement of said member will not be transmitted to said device and rattling in said connection will be absorbed.

17. A feeding mechanism for sewing machines, including means for changing the feed-movements during the operation of the machine, comprising a lever, a device under control of the operator, a flexible connection between the two, and means for controlling the slack in the flexible connection. 90

18. A feeding mechanism for sewing machines comprising a lower feeding device; an upper feed-foot coöperating with said feeding device; means for actuating the said device and foot; and means for bodily lifting the foot from coöperation with said device including a normally stationary spring-controlled lever, a device under control of the operator, and a chain-connection between the two. 100

19. A feeding mechanism for sewing machines comprising a lower feeding device; an upper feed-foot coöperating with said feeding device; means for actuating the said device and foot; and means for bodily lifting the foot from coöperation with said device including a normally stationary spring-controlled lever, a device under control of the operator, and connecting means between the two including a chain and an adjustable 110 arm.

20. A feeding mechanism for sewing machines including a feed-dog-carrying bar, means for actuating the bar and regulating the throw thereof, including a curved lever having a sliding connection with said bar, a rocking-frame, a lever pivotally carried thereby, and a sliding connection between said lever and the curved lever. 115

21. A feeding mechanism for sewing machines comprising a feed-dog-carrying bar, means for actuating, and regulating the throw of, said bar, including a curved lever supported below the bar and having a sliding connection therewith, a rocking-frame, a lever connected thereto, and a connection between said lever and the curved lever permitting adjustment of the one relatively to the other. 125

22. A feeding mechanism for sewing ma- 130

- chines including two feed-bars, a rocking-frame, a curved lever having a fixed pivot and operatively connected to one of said bars, actuating connections between the 5 rocking-frame and the curved lever and between the rocking-frame and the other of said bars, and means, operable during the running of the machine, for controlling the relative movements of the two feed-bars.
23. A feeding mechanism including two feed-bars one of which is carried by the other, a rocking-frame, means between the frame and one of the bars for actuating the latter, means between the frame and the 10 other of said bars for actuating the latter and regulating the movements thereof, and a controlling mechanism including a spring for holding the said actuating and regulating means in a normal adjusted position.
24. A feeding mechanism for sewing machines including two feed-bars, a rocking-frame connected to and actuating one of said bars, means for actuating and regulating the movements of the other of said bars, 15 including a lever connected to said latter bar and to the frame of the machine, and a lever pivoted to the rocking-frame between its ends and having a freely sliding connection at one end with the first lever, and having its other end free for manipulation.
25. A feeding mechanism for sewing machines including two feed-bars, a rocking-frame, means connecting said frame with one of the bars for actuating the same, 20 means connecting said frame with the other of said bars for actuating and regulating the movements thereof, and means including a lever carrying a duplex feed-regulating device coöperating with the rocking-frame to limit the action of the regulating 25 means.
26. A feeding mechanism for sewing machines comprising a driving-shaft, a plurality of feeding-devices, and positive driving 30 connections between the shaft and said devices for actuating the latter, and means located below the cloth-plate of the machine, and connecting with the driving connections whereby one of the feeding-devices may be given movements of varying lengths relatively to the other of said devices during the 35 operation of the mechanism.
27. A feeding mechanism comprising a driving-shaft, a rocking-frame, a feed-bar 40 journaled upon said frame and carrying a dog, connections between the shaft and frame, connections between the frame and bar, said latter connections including a controlling-device, accessibly disposed so as to be under control during the operation of the 45 machine, for controlling the operation of the bar, whereby the action of the latter may be changed consonantly with the direction and extent of movement of said device and while 50 the machine is at speed.
28. A feeding mechanism comprising a plurality of feed-bars, each bar carrying a feed-dog and said dogs being arranged in parallelism; and actuating mechanism for said feed-bars, including means for varying 55 the action of one of said devices relatively to the other during the operation of the machine, and also including means whereby such variations may be gradually increased or decreased between two predetermined 60 limits.
29. A feeding mechanism for sewing machines comprising a feed-bar carrying a dog; a second feed-bar carrying a dog in parallelism with the other dog; means for actuating 65 said bars; means for regulating the throw or feed movement of one of said bars relatively to the other; and treadle-operated means for controlling the feeding action of said latter bar, said means being accessibly presented to 70 the operator so that he may actuate the same during the operation of the machine.
30. A feeding mechanism for sewing machines comprising a plurality of feed-dog-carrying bars; means for regulating the 75 movements of one of said bars relatively to the other; and treadle-operated means for controlling the action of said latter bar whereby predetermined extremes of adjustment may be instantly obtained, said controlling means being accessibly presented to 80 the operator so that he may actuate the same at any time during the operation of the machine and have both his hands free for handling the work.
31. A feeding mechanism for sewing machines comprising a feed-dog-carrying bar; an auxiliary feed-bar; means for actuating 85 said feed-bars; means for adjusting the movement of one of the feed-bars relatively to the other; means for regulating the action of the latter feed-bar in respect of its extremes of feed movement; and treadle-operated controlling means for changing the throw of the latter feed-bar as well as for 90 obtaining predetermined extremes of adjustment, said means being accessibly presented to the operator so that he may operate the same at will and have both his hands free for handling the work.
32. A cloth-feeding mechanism having, in combination, a device for engaging the bottom of the work; a device for engaging the top of the work; means for giving said devices relative action; a treadle-operated controlling means coöperating with one of said devices for manipulating the same to change its action on the work at the will of the operator; and an independent controlling 100 means coöperating with the other of said devices for manipulating the same at the will of the operator.
33. In combination, a stitch-forming mechanism; a feeding mechanism for moving the work past the stitch-forming mecha- 105

5 nism; an auxiliary mechanism coöperating with the feeding mechanism for engaging and controlling the work; a presser-foot mechanism coöperating with the said feeding and auxiliary mechanisms; and a controlling mechanism coöperating with the presser-foot mechanism, for modifying the action of the feeding and auxiliary mechanisms on the work, said controlling mechanism being accessibly presented to the operator to be actuated by the latter at will.

10 34. In combination, a stitch-forming mechanism, a feeding mechanism including main and auxiliary bars, means for raising and lowering said bars simultaneously, means for giving said bars independent feed movements, including a treadle-operated controlling device coöperating with one of the bars for modifying the action of the latter during the operation of the machine and without affecting the stitching action thereof or varying the stroke of the other feed-bar.

15 35. In combination, stitch-forming mechanism, feeding mechanism including a main and an auxiliary feed-bar arranged in parallelism, means for imparting the rise and fall to said bars, means for imparting the longitudinal movements to said bars, including a treadle-operated controlling means for controlling the action of one of the bars during the operation of the machine and without affecting the stitching action thereof, and without varying the stroke of the other feed-

20 35. bar.

36. In combination in a feeding mechanism, a main and an auxiliary feed-bar, a driving-shaft, means for actuating said bars including a rocking-arm, an adjustable connection between said arm and the driving-shaft, a controlling-device, independent of the adjustable connection, connecting said

25 arm with one of the bars whereby the motion of the arm imparted by the driving-shaft may be modified in the said bar without varying the action of the other feed-bar; and means whereby the controlling device may be shifted during the operation of the machine.

30 37. In combination in a feeding mechanism, a main and an auxiliary feed-bar, a driving-shaft, a rocking-arm, an adjustable connection between the driving-shaft and said arm, a driving connection between one of the feed-bars and said arm, a driving connection between said arm and the other feed-bar, said latter driving connection including a controlling lever, with connections accessibly presented to the operator whereby, during the running of the machine, the action of said other feed-bar may be modified.

35 38. A feeding mechanism having, in combination, a main and an auxiliary feed-bar, common means for actuating said bars, means for adjusting the movement of one of said bars, adjusting means for varying the stroke of the other bar, said latter means being connected with said bar and including parts having a loose and sliding connection with each other, and means arranged accessibly to the operator and connecting with said adjusting means whereby, during the operation of the machine and without varying the stroke of the first-named feed-bar, the stroke of the last-named bar may be varied.

In testimony whereof I have hereunto signed my name in the presence of two subscribing witnesses.

JOHN P. WEIS.
